AUTOMATIC CRAB-CATCHING DEVICE

Application filed July 11, 1929. Serial No. 377,566.

This invention relates to fishery and has special reference to a boat equipped to catch crabs, the boat being preferably termed a crabbing boat.

5 In the crab fishery it is common to use long lines, sometimes a mile or more in length. These lines have their ends attached to buoys moored in position by suitable anchorages at intervals along such a line, are short lines 10 carrying the baits. These lines rest on the bottom and from time to time the crabbers start at one buoy and haul the boat along by the line to the other buoy. This, of course, lifts the line from the bottom where it normally lies and such crabs as cling to the baits are brought to the surface so that a dip net 15 may be used to lift them out of the water into the boat. This operation is frequently termed "under-running the line".

20 This method is difficult to carry into proper effect by a single person as it is not easy, especially in rough or windy weather, for a single person to handle both the line and the dip net and many crabs escape after being brought up to the surface. Even when the boat is manned by two persons, one to handle the line and the other the net, many crabs are lost by their dropping the bait before the net can be gotten in position to lift them.

25 One important object of the present invention is to provide an improved form of crabbing device whereby practically all crabs brought up in under-running the line will be caught.

30 A second important object of the invention is to provide an improved crabbing device which may be combined with a motor boat and in which the operations of under-running the line and catching the crabs will be entirely automatic so that the service of only one person is necessary in the boat.

35 A third important object of the invention is to provide a motor boat supported crabbing device so that extremely long lines may be used without making the work too burdensome and with a great saving in time.

40 A fourth important object of the invention is to provide a novel arrangement of elevator 45 for lifting the crabs into the boat, the elevator

having its operation effected by the movement of the boat through the water.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of a boat equipped with this invention.

Figure 2 is a plan view thereof.

Figure 3 is a section on the line 3—3 of Figure 2.

Figure 4 is an enlarged section on the line 4—4 of Figure 1.

Figure 5 is an enlarged view showing a portion of the line and a bait holder attached thereto.

Figure 6 is a view similar to Figure 3 but showing a modification of the invention.

In the embodiment of the invention here shown there is disclosed a boat 10 having suitable propelling means as indicated by the engine 11. On the gunwales 12 of the boat are mounted bearings 13 supporting the forward shaft 14 and the after shaft 15. These shafts extend athwartships of the boat and project outboard. The forward shaft has its outboard end bent forward to support a bracket 16 whereon is mounted a forward roller 17 aft of which is a second roller 18. On the outboard end of the after shaft is mounted a line roller 19.

The line 20, with the device in use, runs up from the bottom out of the water and passes over the roller 17, under roller 18 and over roller 19 back into the water. Projecting from the side of the boat on the same side as the rollers are brackets 21 which support a scoop frame 22 having an after parallel sided portion of channel or trough shape and a forward laterally flaring and vertically tapering portion 23. This frame is covered with wire mesh cloth 24 and at the forward and after ends of the parallel sided portion, as well as at suitable places along said portion, are conveyor rollers 25 adjacent the bottom of this

scoop and a conveyor belt 26 of fabric or wire mesh runs over these rollers. This scoop is open at its after end and at that end is provided with an athwartship extension 27 which runs inboard over the gunwale. It will be noted that this scoop lies below the line 20 and that its forward end dips into the water while the after end has its bottom at least as high as the gunwale at the point opposite said after end.

Journaled below the after end of the scoop is a shaft 28 whereon is mounted a partially submerged paddle wheel 29 which is connected by any suitable gearing or driving connection with the shaft of the after roller 25. This driving connection is here indicated by a crossed belt 30 and pulleys 31 but beveled gears may be employed instead and in most cases are preferred. Any other form of gearing may also be used.

Along the line 20 are spaced bait holders 32 which are hung from clamping sleeves 33 clamped at desired intervals on the line.

In the modification shown in Figure 6 the scoop is provided with an open bottom portion 34 and a conveyor 35 is supported on brackets 36 in such manner that its upper run closes this open bottom, the upper run of the conveyor thus forming a movable floor or bottom section for the scoop.

In using this boat no rudder is necessary as the line 20 guides the boat and in operation the boat is positioned at one buoy and headed toward the other. The portion of the line running towards the other buoy is, of course, that which runs over the forward line roller. The engine is now started and, as the boat moves toward the other buoy the line will be under-run and the paddle wheel will rotate to operate the conveyor. Any crabs clinging to the baits will be lifted so they are above the forward end of the scoop, being shaken off as the bait lines strike the forward line roller. Due to the flow of water past the boat these crabs will be carried onto the conveyor end by it conveyed up to the athwartships end and thus pass into the boat.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. The combination with a boat; of means carried by the boat for under-running a crab line, a scoop carried by the boat and having its forward end below water beneath the crab line and its upper end leading into the boat,

a conveyor in said scoop arranged to move crabs in the scoop from the forward to the after end of the scoop, and means operated by the movement of the boat through the water for operating said conveyor.

2. The combination with a boat; of means supported at the side of said boat for under-running a crab line, and a scoop supported in fore and aft position at the side of the boat beneath the raised portion of the crab line and having its forward end projecting below the water and its after end above the gunwale of the boat at said after end, the after end of said scoop having an athwartships portion extending inboard over said gunwale and open at its inner end.

3. The combination with a boat; of means supported at the side of said boat for under-running a crab line, a scoop supported in fore and aft position at the side of the boat beneath the raised portion of the crab line and having its forward end projecting below the water and its after end above the gunwale of the boat at said after end, the after end of said scoop having an athwartships portion extending inboard over said gunwale and open at its inner end, and a conveyor in said scoop arranged to move crabs in the scoop from the forward to the after end of the scoop.

4. The combination with a boat; of means supported at the side of said boat for under-running a crab line, a scoop supported in fore and aft position at the side of the boat beneath the raised portion of the crab line and having its forward end projecting below the water and its after end above the gunwale of the boat at said after end, the after end of said scoop having an athwartships portion extending inboard over said gunwale and open at its inner end, a conveyor in said scoop arranged to move crabs in the scoop from the forward to the after end of the scoop, and means operated by the movement of the boat through the water for operating said conveyor.

5. The combination with a boat; of means carried by the boat for under-running a crab line, a scoop carried by the boat and having its forward end below water beneath the crab line and its upper end leading into the boat, a conveyor in said scoop arranged to move crabs in the scoop from the forward to the after end of the scoop, a driving drum in said scoop carrying the after end of said conveyor, a shaft for said drum extending outboard of the conveyor, a partly submerged paddle wheel below the after end of said conveyor, a shaft supporting said wheel, and a driving connection between said shafts.

6. The combination with a boat; of means supported at the side of said boat for under-running a crab line, a scoop supported in fore and aft position at the side of the boat beneath the raised portion of the crab line

and having its forward end projecting below the water and its after end above the gunwale of the boat at said after end, the after end of said scoop having an athwartships portion extending inboard over said gunwale and open at its inner end, a conveyor in said scoop arranged to move crabs in the scoop from the forward to the after end of the scoop, a driving drum in said scoop carrying the after end of said conveyor, a shaft for said drum extending outboard of the conveyor, a partly submerged paddle wheel below the after end of said conveyor, a shaft supporting said wheel, and a driving connection between said shafts.

15 In testimony whereof we affix our signatures.

FRANK BURNS.
